Primary Examiner — Jennifer Rivard*Assistant Examiner* — Jenny lou M Binas(74) Attorney, Agent, or Firm — Rumit Ranjit Kanakia(57) CLAIM

The ornamental design for a mop, as shown and described.

DESCRIPTION

FIG. 1 is a perspective view of a mop showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a rear perspective view, shown in an open state. The broken lines in the figures are for the purposes of illustrating portions of the mop, which form no part of the claimed design.

1 Claim, 8 Drawing Sheets(56)
